UNITED STATES PATENT OFFICE.

ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

SPRING-PAD CONSTRUCTION.

Application filed September 4, 1924. Serial No. 735,839.

This invention relates to spring pads, for pressing machines, as garment and laundry pressing machines, and has for its object a particularly simple, efficient and economical construction of the springs of said pad, whereby they are readily assembled in the pad.

The invention consists in the novel features and in the combinations and constructions hereinafter set forth and claimed.

In describing this invention reference is had to the accompanying drawings in which like characters designate corresponding parts in all the views.

Figure 1 is a plan view, partly broken away, of one embodiment of my invention.

Figure 2 is a fragmentary detail view of the springs.

Figure 3 is a fragmentary detail view of the spring blanks before folded into position to be placed in the pad.

This pad comprises coiled springs interposed between the base and top or the top and bottom plates of the pad, the end coils of the springs being connected by wires integral therewith forming straightened extensions, and the lower end coil of each spring being connected to the lowermost coil of an adjacent spring by such extension, and the uppermost coil of each spring being connected to the upper coil of another adjacent spring by such integral extension of the upper coil of the spring.

These connecting wires form rests or seats for the upper and lower plates, and hold the spring from relative movement or displacement, and also hold any one spring from movement relatively to the upper and lower plates between which the springs are interposed. If desired the connecting pieces or some of them may be secured to the plate it overlies.

1 and 2 designate the upper and lower plates of the pad, the upper plate being usually a wire mesh, and 3 designates the fabric covering or wrapper, all as will be understood by those skilled in the art. The lowermost plate is usually of sheet metal and may be perforated for permitting steam to pass through the padding from the buck to the surface of the pad or to the garment or other article being operated on.

It will be understood that the pad is placed on either the lower buck or the press

head of a standard pressing machine, it being usually mounted on the lower buck.

4 designates the coil springs, and 5 designates the integral connecting wires, connecting the lowermost coil 6 of each spring to the lowermost coil 6 of an adjacent spring, and 7 designates an integral connecting piece between the uppermost coil 8 of each spring and that of another adjacent spring.

A plurality of these springs are coiled up from a single wire in straight formation as seen in Figure 3 with the springs 4 connected by connecting portions 5 and 7, and the springs are folded at right angles to the connecting portions into the form shown in Figure 2.

In use a single series of springs may be laid over the entire area of the plate 1, or such single series may be split up into several sections depending upon the length of the wire forming the springs and connecting portions, or the springs may be formed up into small mats and several of these mats laid on the base plate to cover the same. These mats may be square or triangular, or any other geometrical figure.

If desired the springs may be secured to either the top or lower plate at intervals by suitable fastening means as rivets 9, coacting with connecting portions 5 or 7. When the pad formation is used no riveting or other fastening is necessary, but when the series of springs follow a line fastening means may be used at intervals.

This spring construction is particularly advantageous in that the springs are readily and economically assembled in the pad, and are held by means inherent in their construction from relative displacement and from individual displacement.

What I claim is:

1. A spring pad comprising upper and lower plates and a padding consisting of coiled springs connected by connecting pieces at their upper ends and at their lower ends by connecting pieces forming continuations of the end coils of the springs, the connecting pieces being arranged against the opposing sides of the plates.

2. A spring pad comprising upper and lower plates and a padding consisting of coiled springs connected by connecting pieces at their upper ends and at their lower ends by connecting pieces forming continuations

of the end coils of the springs, the connecting pieces being arranged against the opposing sides of the plates, and the connecting pieces at like ends of the springs being secured to one of the plates.

3. A spring pad for pressing machines comprising a pair of opposed plates and coiled springs arranged in series, wires forming continuations of the end coils of the

springs connecting the springs together, the connecting wires being positioned to thrust against the inner sides of the opposing plates of the pad.

In testimony whereof, I have hereunto signed my name, at Syracuse, in the county of Onondaga, and in the State of New York, this 20th day of August, 1924.

ALBERT B. CLISSON.
